UNITED STATES PATENT OFFICE.

ADOLPH A. CAILLE, OF DETROIT, MICHIGAN.

SLUG-DETECTOR FOR CHECK-CONTROLLED MACHINES.

Application filed December 30, 1925. Serial No. 78,316.

The present application relates to check or coin controlled or operated machines or devices.

Among the objects of the invention is to provide means by which operation of such machines or devices with spurious checks or coins can be readily detected although the spurious check or coin may have the correct shape, size and weight.

10 Another object is means by which examination may be made of the last check or coin used in operating the machine and of the several preceding checks or coins.

With these and other objects in view, as 15 will readily occur to those skilled in the art, the invention consists broadly in mechanism intermediate the check slot, and its controlling devices, and the check depository, which mechanism will exhibit to view 20 through a suitable window the last several checks used for operation before passing them on to the depository.

Reference should be made to the accompanying drawings, in which:

25 Fig. 1 is a side view of the device as applied to a check controlled "slot machine";

Fig. 2 is a perspective view of the detached device showing more particularly the front;

30 Fig. 3 is a rear elevation thereof; Fig. 4, is a vertical section thereof on the line 4-4 of Fig. 3;

Fig. 5 is a vertical sectional view on the line 5-5 of Fig. 3; and

35 Fig. 6 is a view similar to Fig. 5 but with the parts in a different position.

The form of device chosen for the purpose of illustration and description is one adapted to use with a well known coin or check 40 operated machine and a sufficient portion of the latter is shown to indicate the mechanism used in operating the device. It is to be understood, however, that the invention is not limited to use with such machines but 45 may be adapted without material change to other machines than that shown.

In the drawings, the device is shown as 50 consisting of a rectangular frame or tray 10, divided, in its upper portion by a longitudinal partition 11, into two channels connecting at their lower ends, there being a diagonal partition 12, arranged to cause checks from the right hand channel to pass into the bottom of the left hand channel.

55 The left hand channel is provided with a longitudinal slot 15, through which extend

the fingers 16 of a conveyor or elevator (to be described) which raises the checks from the bottom of this channel and finally drops them through the opening between bridge 60 piece 17 and the floor of the channel into a chute extending to a suitable receiver or depository.

The back of the tray 10 is provided with suitable means 20 by which it may be secured to the machine proper and the sides are provided with channel members 21 adapted to permit covering the tray with a glass cover plate 22 so that checks in the tray are exposed to outside view, it being 70 understood that the whole machine and tray will be suitably covered except for the window thus formed.

As mentioned above, the fingers 16 form parts of a conveyor for elevating the checks from the lower end of the tray to the top thereof. This conveyor is shown best in Figs. 3 to 6, and, in the present instance, consists of the three fingers 16 carried pivotally as at 27 on a bar 25 slidably mounted on the 75 back of tray 10 in suitable guides 26. The fingers are held in elevated or active position by connecting them with springs 28 under slight tension, causing them to press up against the under side of the glass but permitting them to be depressed to pass under a check.

Bar 25 is connected at its lower end to a spring 30 which in turn is connected to the operating lever of the machine and is adapted to pull down the bar 25 when the said lever is moved without the insertion of a suitable check in the proper place, the bar 25 is held against movement by means of a pawl 31 90 spring-pressed into notch 32. Further, the elevator is returned upwardly by means of the bar 33-34 connected parallel to spring 30 and to the same parts, this bar being made extensible to permit the movement of 95 its lower connection without operation of the elevator.

In order to retain the checks in elevated intermediate position, the additional spring fingers 35 are arranged to extend through the tray floor in slots 36 extending laterally from slot 15. These fingers 35 are pivoted on the back of the tray at 37 and located so as to retain the checks elevated by the lower two fingers 16.

110 In addition to its function as a pawl for retaining bar 25 in elevated position, pawl

31 carries a finger 40 extending through an opening 41 in the floor of the tray in the right channel. When the pawl releases bar 25 and the latter drops, the finger 40 extends far enough into the tray to hold the incoming check and prevent its passing into the bottom of the elevator channel until the elevator has lifted therefrom a previously used check. When the elevator has risen nearly to the top, the bar 25 lifts the pawl and finger 40 so as to retract the latter and allow the last check used to drop into the bottom of the elevator channel.

The device, therefore, as illustrated, will present to view the last four checks used to operate the machine and thereby permit an attendant to detect the use of improper checks to within several operations of the machine.

20 The device as applied to a well known form of check controlled machine is shown in Fig. 1.

In this figure, the device is shown as a whole at 50 secured to the machine, which latter comprises a frame 51 carrying the usual mechanism. This mechanism is adapted to be set in motion by depressing the lever 52 and thus storing energy in a spring (not shown), which energy is released to the movable parts, the release being controlled by a suitable governor, such as the air fan 52^a, so that the parts return to rest position more or less slowly.

When the lever 52 is depressed, without insertion of a coin or check in the receiver 53, lever 54 is moved toward the left and through its arm 55 lifts bar 56 and with it means (not shown) carried by the latter to prevent actuation of the mechanism. However, when the lever 52 is depressed, after insertion of a check, lever 54 is prevented by the check from movement and with it bar 56 is prevented from movement until after the mechanism has begun to be actuated. Under these conditions, bar 56 continues to rise till near the end of the stroke of lever 52 when it is given a quick upward movement.

50 In this quick upward movement the bar 56 through a stud 57 gives lever 58 a quick movement and the latter in turn depresses the arm 59 carried by pawl 31. When arm 59 is depressed it releases pawl 31 from notch 32 in the elevator bar 25.

55 In the meantime, the depression of lever 52 has caused the mechanism of the machine to operate lever 65 and has thereby extended spring 30, so that when the pawl 31 releases the bar 25, the latter is immediately drawn to its lowest position. When the conveyor is in this position, pawl 31 can and does move forward to project finger 40 through opening 41 where it is in the path of the check just used to operate the machine.

60 65 As the machine mechanism returns slowly

to rest, the conveyor bar 25 slowly raises and lifts the several preceding checks until at last the finger 40 is withdrawn and the last check drops to the lowest position in the left hand channel of the tray.

70 While the form of device shown in especially adapted to be used with the type of check controlled machine shown, it permits of broader application and it is contemplated to use it with any check controlled 75 or operated mechanism for the purpose of aiding in the detection of the use of improper checks or coins.

Having now described the invention and the preferred form of embodiment thereof, so it is to be understood that said invention is not to be limited to the exact details shown and described but only by the scope of the claims which follow.

Claims:

1. A check or coin controlled machine comprising a substantially upright tray to receive checks from the check operated or controlled mechanism, means to guide said checks to the bottom thereof, an elevator in said tray to lift said checks from the bottom over the top edge of said tray and drop them into a suitable chute, said elevator being constructed and arranged to require several operations to convey a check the length of said tray, and means whereby said check is visible to the outside during said several operations.

2. A check or coin controlled machine comprising a substantially upright tray to receive checks from the check operated or controlled mechanism, a partition dividing said tray into two channels connected at their lower ends, means in one of said channels for elevating checks from the lower to the upper end thereof, the other of said channels being open at its upper end to receive said checks from the said mechanism, means to guide said checks from the second channel into the bottom of the first channel, and means to detain a check in said second channel until said elevator has removed a preceding check from the bottom of said first channel.

3. A check or coin controlled machine, including a chamber intermediate the check control mechanism and check depository and having a transparent cover therefor, a step conveyor in said chamber having a plurality of steps, means for guiding a check from the said control mechanism to the pick-up end of the conveyor, means controlled by said control mechanism for actuating said conveyor a step, and means for retaining a check thus advanced in its advanced position.

4. A check or coin controlled machine including a chamber in which a plurality of the last used checks are exposed to view, said chamber being provided with a conveyor, the actuation of which is controlled by the check

- control mechanism, said conveyor comprising a longitudinally slideable bar carrying a plurality of spring fingers extending into the chamber, other spring pressed fingers in fixed position in the chamber, the latter fingers being arranged to retain checks advanced by said conveyor fingers, means to retract said conveyor, and means to advance it slowly.
- 5 5. In a slug detecting device for coin or check controlled machines, a check conveyor arranged to convey singly a plurality of checks, a tension spring to actuate said conveyor in one direction, and an extensible rod parallel with said spring adapted to actuate 15 said conveyor in its other direction.
- 10 6. In a slug detecting device for coin or check controlled machines, a check conveyor arranged to convey singly a plurality of checks, a tension spring to actuate said conveyor in one direction, an extensible rod parallel with said spring adapted to actuate said conveyor in its other direction, and means to control the rate of movement in said other direction.

ADOLPH A. CAILLE.
